UNITED STATES PATENT OFFICE

1,969,455

SANITARY CUT-OFF FOR TUBES AND THE
LIKE

Cora E. Cope, San Antonio, Tex.

Application May 7, 1932, Serial No. 609,798

1 Claim. (Cl. 221—60)

This invention relates to an improved sanitary cut-off mechanism for tubes containing different substances; however, my invention as illustrated in the drawing has particular reference to a tooth paste tube.

The primary object of my invention is to provide a conventional sanitary cut-off for tooth paste tubes accessibly mounted thereon, and to eliminate and prevent the tooth brush from contacting the mouth of the tube which is very insanitary where several or even one person is using a certain brand of paste, whereby the accumulation of germs on the mouth of the tube which is the direct cause of many mouth diseases is entirely prevented.

Another object of my invention is in the novel construction whereby it is so constructed that it can be applied to the ordinary paste tube without interfering with the conventional screw cap.

Still another object is in the particular shape of the convenient handles whereby the cut-off can be actuated with the operator's thumb to cause an oscillating movement of the cut-off, and regardless of the position of the cut-off, one or the other handle will extend beyond the mouth of the tube, due to the peculiar manner the handles are bent.

Another feature of my invention is the simple construction and the economical manufacturing cost.

With these chief objects in view, the invention has particular reference to its salient features of construction and arrangement by which the said objects are attained, and which will be enumerated in the course of the following description of detail and illustrations.

In the accompanying drawing like characters of reference indicate like parts in the several views and;

40 Figure 1 is a front elevational view showing my invention applied to the tube.

Figure 2 is a front elevational view with the conventional screw cap removed and having my cut-off in an upright position.

45 Figure 3 is a side elevational view showing the invention applied and its oscillating movement.

Figure 4 is an enlarged fragmentary view showing the invention in detail and the novel construction thereof.

50 Proceeding now more in detail with the drawing, attention is directed to Figure 1, in which is illustrated the invention applied to the tube 1. In this view the tube 1 is fully assembled, having the screw cap 4 thereon also showing the convenient handles 2 on opposing sides, termi-

nating in pivots 6 pivotally mounted on the neck 5 in indentures 7 clearly disclosed in Figures 2 and 4.

In Figure 3 is illustrated the oscillating movement of the cut-off member 3 in an upright position, pivotally mounted on the threaded neck 5. Cut-off member 3 has a frictional clearance at the mouth of the neck 5 to effect a clean cut of the paste when dispensed and as desired, which is clearly shown in Figure 4 and is illustrated by the simple construction of the twisted wire forming the cut-off.

While only one form of each element in the invention has been described herein it should be understood that the invention is capable of considerable variation, and such variation as is within the scope of the annexed claim is considered within the spirit of the invention.

I claim:

In combination with a collapsible tube container having a shoulder at one end terminating in an extended reduced neck provided with a discharge port longitudinally therethrough and a closure cap therefor, a cut-off device attached to the discharge end of said container, said cut-off device being constructed from a single length of suitable wire bent into the form of a U, the intermediate portions of the wire between the ends of the leg members of the U and the free ends of the wire being bent upon themselves and twisted to form oppositely and upwardly directed handle members, the free ends of the wire being bent inwardly at substantially right angles to the legs of the U to form pivots which engage recesses in opposite sides of the tube neck adjacent the ends of the leg members of the U, whereby the cut-off device is pivotally mounted on the container neck in such position that when oscillated in either direction by means of the handles the closed end of the U is passed over the port in the end of the neck when the closure is removed to sever the extruded ribbon of paste, and thereafter is swung through an arc and brought to rest on the shoulder of the tube to permit the subsequent attachment of the cap on the neck.
